F. G. Fischer,

Attorney

UNITED STATES PATENT OFFICE.

LINN W. MILLIS, OF KANSAS CITY, MISSOURI.

DAMPER-REGULATOR.

1,379,832.

Specification of Letters Patent. Patented May 31, 1921.

Application filed March 10, 1921. Serial No. 451,262.

To all whom it may concern:

Be it known that I, LINN W. MILLIS, a citizen of the United States, residing at Kansas City, in the county of Jackson and State of Missouri, have invented certain new and useful Improvements in Damper-Regulators, of which the following is a specification.

My invention relates to improvements in 10 damper regulators for furnaces and other heaters which are generally located in the basement and provided with a smoke damper and a cold air check valve, and the essential purpose of the invention is to connect 15 said cold air check valve and the smoke damper with a lost motion sufficient to allow the smoke damper to be almost entirely closed without affecting the position of the check valve, but when moved beyond the 20 limit of its lost motion, operates to open the check valve for the admission of cold air to the draft-pipe.

Another feature of the invention is the provision of a flexible connection for controlling 25 the smoke damper from an upper floor.

In order that the invention may be fully understood, reference will now be had to the accompanying drawing, in which:

30 Figure 1 is a side elevation of the invention applied to the draft pipe of a furnace.

Fig. 2 is an enlarged plan view.

Fig. 3 is an irregular longitudinal section on line III—III of Fig. 2.

35 Fig. 4 is an end elevation.

A designates a furnace which is provided with a draft pipe 2 having a housing 4 at its upper portion.

6 designates the smoke damper arranged 40 in the draft pipe 2 and fixed to a spindle 8 journaled at its lower end in the draft pipe 2 and at its upper portion in the housing 4. The upper portion of the spindle 8 is formed into a crank arm 10 having a loop 45 12 intermediate its ends and an eye 14 at its outer end.

16 designates the cold air check valve which is mounted upon a spindle 18 journaled in opposite sides of the housing 4 to 50 normally close an air inlet 17 in the upper portion of said housing 4. The check valve 16 is self-closing, it being weighted at one side as indicated at 19, for that purpose. A flange 20 on the housing 4 serves as a stop 55 for the check valve 16 when the same moves to closed position.

22 designates a link connected at one end to an arm 24 projecting from the check valve 16 and having a sliding connection at its opposite end with an eye 25 on the crank arm 60 10, to allow the smoke damper 6 to have limited independent movement of the check valve 16. The extent of such limited independent movement is determined by stops 26 and 28, spaced apart upon the link 22. 65

30 designates a flexible connection whereby the smoke damper 6 may be closed or partly closed from an upper floor. Said cable 30 extends around a guide sheave 32 and is secured at its lower end to the eye 14 70 of the crank arm 10.

34 designates a flexible connection connected to the loop 12 and provided with a weight 35 to open the smoke damper 6 when the cable 30 is lowered. As shown on the 75 drawing the flexible connection 34 extends over a guide sheave 36.

In practice the smoke damper 6 may be closed or partially closed by pulling upwardly on the flexible connection 30. Owing 80 to the lost motion between the crank arm 10 and the link 22 the latter will not be actuated to open the check valve 16 until the eye 25 of the crank arm 10 impinges against the stop 28 and moves the link 22 forwardly. 85 When desired the smoke damper 6 is restored to open position by lowering the flexible connection 30 which permits the crank arm 10 to be drawn backwardly by the flexible connection 34 and the weight 35, 90 to the position disclosed by Figs. 2 and 3. As the crank arm 10 moves backwardly the eye 25 moves away from the stop 28 and allows the check valve 16 to close.

From the foregoing description it will be 95 understood that the smoke damper 6 can be almost entirely closed to check the fire in the furnace before the check valve 16 is opened to admit cold air to the draft pipe 2. By thus being able to control the smoke 100 damper 6 to a large degree independently of the check valve 16, a considerable saving in fuel is effected as under ordinary circumstances the fire in the furnace can be controlled with the smoke damper 6 and without cooling off the draft pipe 2 by admitting cold air through the inlet 17. This is an important feature, because when the temperature of the draft pipe 2 is lowered by the admission of cold air through the inlet 110 17, it requires a considerable consumption of fuel to again heat said draft pipe 2 to a

sufficient degree to obtain an efficient draft, whereas if the draft is largely controlled by the smoke damper 6 the temperature of the draft pipe 2 is not lowered by the admission 5 of cold air, and hence only a relatively small amount of fuel is consumed in restoring the draft to the desired temperature.

While I have shown the invention applied to a horizontal section of draft pipe 10 it will operate equally as well on an inclined, or vertical section, as the guide sheaves 32 and 36 are mounted in holders 40 and 42, respectively, which are loosely connected to the housing 4 to accommodate themselves to 15 the different angles at which the cables may be arranged. Other changes may be made in the construction, arrangement and combination of parts, falling within the spirit and scope of the claims.

Having thus described my invention, what I claim and desire to secure by Letters Patent, is:

1. In a device of the character described, a draft-pipe having an opening for the admission of cold air, a smoke damper operably mounted in said draft-pipe, a check-valve to control the admission of cold air to the draft-pipe through the opening, and a connection between the smoke damper and 25 said check valve having lost motion, whereby the former may be closed, or practically closed, before the latter is opened.

2. In a device of the character described, a draft-pipe having an opening for the admission of cold air, a smoke damper operably mounted in said draft-pipe, a check-valve to control the admission of cold air to the draft-pipe through the opening, a connection between the smoke damper and said 35 check valve having lost motion, whereby the former may be closed, or practically closed, before the latter is opened, and means for closing the check-valve as the smoke damper moves toward open position.

3. In a device of the character described, a draft-pipe having an opening for the admission of cold air, a smoke damper oper-

ably mounted in said draft-pipe, a check-valve to control the admission of cold air to the draft-pipe through the opening, a connection between the smoke damper and 50 said check valve having lost motion, whereby the former may be closed, or practically closed, before the latter is opened, and a weight on the check valve to close the same as the smoke damper moves toward open 55 position.

4. In a device of the character described, a draft-pipe having an opening for the admission of cold air, a smoke damper operably mounted in said draft-pipe, a check-valve to control the admission of cold air to the draft-pipe through the opening, arms 60 for actuating the smoke damper and the check valve, and an element connected to one of said arms and having a lost motion 65 connection with the other arm so that the smoke damper may close, or partially close before the check-valve is opened.

5. In a device of the character described, a draft-pipe having an opening for the admission of cold air, a smoke damper operably mounted in said draft-pipe, a self-closing check-valve to control the admission of cold air to the draft-pipe through the opening, arms for actuating the smoke damper 70 and the check valve, an element connected to one of said arms and having a lost motion connection with the other arm so that the smoke damper may close, or partially close before the check-valve is opened, 75 spaced stops at opposite sides of one arm and fixed to said element to limit its lost motion, manual means for moving the smoke damper arm in one direction, and automatic means to move said smoke damper 80 arm in an opposite direction.

In testimony whereof I affix my signature in the presence of two witnesses.

LINN W. MILLIS.
